AIRSHIP MOORING METHOD AND APPARATUS

Application filed January 18, 1930, Serial No. 421,645. Renewed May 26, 1932.

This invention relates to airships, but more particularly to their construction which makes the airship capable of landing on water and bringing them down for a water landing and mooring,—while it also involves the method of mooring airships on water with effective stable flotation.

For the purposes of my invention a construction of airship has been provided which will permit its landing with its own crew, and thereafter, as desired, to provide for taking off from the water,—all of the operations being under control of the crew on board the ship. This is effected by providing a nacelle 15 keel of suitable dimensions for the particular design and type of airship in question, the keel being watertight and extending from the lower surface of the hull skin, the nacelle being airtight in part at least, so as to provide a sufficiently large space into which water may be admitted, as desired, and from which the water may be ejected in part or whole, either for trimming the ship or for lightening the ship when it is desired to rise 20 from the water. Such a nacelle keel is also arranged to minimize the parasite air resistance when the ship is in flight, and also to provide a minimum of resistance to the flow of water when moored on the water. When 25 moored on the water usually by bow line, or as may be by a bridle, either to ground mast, or to a ship or other mooring float or anchorage, the airship will swing-by-the-wind. Under certain conditions of mooring there will 30 be a flow of surface water toward the stern of the ship, so that the sub-structure or supplementary water-riding hull is stream-lined to reduce the strain on the mooring lines, as well as to reduce to a minimum any water 35 resistance while the nacelle is still in contact with the water at the time that the ship is gotten under way, or taxying from the landing to its mooring. A rudder may also be 40 provided in order to aid in stabilizing the position of the ship in the wind, in conjunction with the air rudders on the ship's hull, to meet any conditions of rolling, or to maneuver the ship from any purpose when landed on the water. The interior of the flotation 45 or ballast keel may also be divided into two

or more compartments by bulkheads, and the ballast control in each may be separately manipulated for the purpose of more definite trim of the longitudinal axis of the ship, or otherwise.

While providing for the stable flotation, I also aim to provide the method, and the means self-contained for operation by the ship's crew, for bringing the ship from entire air buoyancy to the surface of the water. 55 It will be understood that in maneuvering the ship in the air it may be brought above the water at the desired place, or approximately so depending upon various conditions. While it may then have an altitude above water 60 level which it is desired to reduce gradually in order to bring the ship to the surface most safely, I provide suitable means to lower from the ship by self-contained apparatus operated on board, that will reach the water 65 and accumulate a suitable amount of water to offset the buoyancy of the ship, and then by manipulation on board, to draw the ship down to the surface. I have found that lowering by suitable lines a cage of sponges, 70 preferably primed, or several "cages" of sponges, they will quickly absorb approximately twenty-one times and more, of their weight of salt water, and therefore provide a vertical anchor which can be made of an 75 aggregate sufficient to properly counteract the lift of the ship,—without "valving" hydrogen or helium. In that manner the water landing can be made without loss of the valuable buoyant gas, so that after reaching 80 the surface of the water the ballast keel may be allowed to fill to the desired trim for maintaining the water surface mooring.

Such lift-anchors may be preferably in 85 pairs, one on either side forward and one on either side aft, and will also serve the purpose to prevent rolling of the ship when the nacelle keel is partially emersed. When however it is desired to clear away ready for 90 flight, the sponge anchors can be squeezed eliminating ninety-five per cent of their weight when full of water, and the water in the ballast keel can then be forced out, and on account of the surplus buoyancy maintained due to not having valved any gas, the 95 100

ship will then rise without difficulty ready for maneuvering in the air.

While this invention may take various forms of construction, and of course modifications in dimensions and arrangement, in the accompanying drawings specific embodiments are illustrated, in which:

Fig. I is a side elevation of a rigid airship moored by the nose, and in stable flotation 10 on the water.

Fig. II is a bottom view of the nacelle keel.

Fig. III is a cross-section of the keel in the plane III—III, of the previous figures.

Fig. IV is a cross-section on the plane IV—15 IV, of Fig. II.

Fig. V is a cross-section on an enlarged scale of the ballast keel, in the plane III—III of Fig. II, including a fragmentary portion of the adjacent airship hull structure.

Fig. VI is a side elevation of an airship 20 with lowering sock or anchors when about to make a water surface landing.

Fig. VII is a front elevation of Fig. VI, showing the ship on the surface of the water, power cars omitted.

Fig. VIII is a fragmentary sectional view of the dry keel section containing the anchor manipulating means.

Fig. IX is a section of one form of a sponge 30 cage, in vertical section, serving to evacuate automatically a substantial part of the water content of the sponge cells.

In the mooring arrangement shown in Fig. I, an airship 1 is moored by the bow line 2, 35 to a mooring tower 3 located as on a small island, with mooring connections 3^a which permit the bow line to be adjusted, such as maintaining it horizontal for the stable flotation position of the ship. The mooring 40 tower attachment being variable vertically, permits the initial mooring followed by bringing the ship vertically downward as by the surplus-weight-anchors, or otherwise, until the ship is moored in stable flotation 45 on the surface of the water.

The nacelle keel 4 is secured to the airship hull structure on the bottom amidships, while its exact longitudinal position will depend upon the structure of the ship. In certain 50 types of ship it may be preferable to have two nacelle keels generally parallel and taking the form of kelson keels, whereby the rolling of the ship when moored on the water may be minimized by regulation of the 55 ballast in the two nacelles. While pairs of right and left supplementary weight water-anchors, in sets of one, two, three or more, may provide for the restriction of rolling, it will be seen that the primary purpose of 60 the water mooring anchors for controlling vertical movement, namely, surplus lift may be dispensed with after the ship has been landed, that is moored to the surface in the case of a double nacelle keel with water-bal-65 last arrangement. Nevertheless, during the

period of mooring for discharge and embarkation, conditions may warrant maintaining the vertical or surplus lift anchors, as well as a portion of water-ballast keel counterbalanced for the airship lift, after it has once been drawn down to the water surface mooring.

In the particular construction illustrated in Figs. I to V the nacelle consists of the transverse frames 5, with the outer sheathing 6 and suitable longitudinal ribs 7, and may contain a central longitudinal bulkhead 8, and transverse bulkheads 9—9^a. At the lowest portion of the nacelle hull skin there are valves 10—10^a suitably arranged, closing the openings 11—11^a, which are preferably a series of ample area valves adjacent the keel 12 of the nacelle, to provide quick inlet and exit of water. Suitable strainers 13 above each valve opening are provided to prevent ingress of anything except water. Suitable rods or valve control stems 14—14^a extend through packing boxes 15 through the airtight roof of the nacelle, which may be the lower hull skin of the airship. These rods reach to a position such as the hand wheels 16—16^a within the hull of the airship, where they may be readily manipulated by the crew for the opening and closing of the valves 10—10^a. The amount of water in the ballast space in the nacelle is indicated by a suitable remote gauge 17—17^a and indicators adjacent the valve control wheels.

On board of the ship, at any suitable place, are pumps 18—18^a connected by pipes 19—19^a to the uppermost area of the roof of the nacelle, at 20—20^a, with air valves 21—21^a positioned accessible to the operator of the valves, thus providing for one or two-man control of each set of water ballast valves, air control for water ejection, and indicators for the ballast condition in the nacelle. Suitable manholes for access for inspection and repair of the nacelle are provided in the airtight roof of the nacelle.

As shown in Figs. II, III and IV, lines of the nacelle keel provide a larger beam near the bow with a taper toward the stern, which is preferable, but maintaining a generally horizontal keel of the ballast nacelle, and at its stern a rudder 22 may be provided operated from the interior of the airship by suitable tiller or steering gear.

The method of mooring by this invention would involve bringing the airship under its air control elevators and rudders to the desired location, and as the keel touches the water some or all of the valves 10—10^a would be opened the desired extent to admit water into the nacelle, and their opening so controlled as to prevent too great a sinking of the nacelle below the surface of the water. While this is being accomplished the bow line 2 may have been run to the mooring mast, or under light wind conditions the trim of

the ship on the water may be first accomplished, and then the out-mooring line secured the desired extent of the ship's position. When so moored, with a suitable small 5 island mooring, the ship may be brought on a stable flotation to a point where the passenger and supply hatch is accessible to a circular wharf around the mooring tower, thereby permitting ready access and egress.

10 However, the conditions of airship operation do not always permit a practical lowering of the ship to water level, that is it may involve too great a speed when dependent upon elevator control, or otherwise, and 15 therefore under such conditions the lift-anchorage method of bringing the ship down to the surface of the water may be accomplished in the method indicated, and forms of construction shown, in Figs. VI to IX. 20 In such case the ship may be brought down to the desired level adjacent or on the water surface, and maneuvered or taxied to the more or less permanent mooring mast floating or on land.

25 In the case of the semi-permanent mooring on the water, and when it is desired to leave the mooring the pumps 18—18^a are operated and the crew control by the valves the inlet of air to the top or roof of the ballast keel, 30 thereby gradually forcing the water out of valves 10—10^a as rapidly as desired, and after clearing the water by the release of the water ballast the ship is prepared to cast off, that is by rising in still air, or in case of a 35 wind it can clear from the bow mooring, and take to the air. Any chance of remaining water may then be ejected by opening the valves and driving ample air from the pumps, either one, or both, or by suitable 40 valves to airpipes leading to each of the several longitudinal sectional compartments. When in the air the manholes may be removed and any desired inspection and cleaning 45 of the interior of the nacelle is accomplished.

It is appreciated that landing in any fair-way the chance of valves being clogged by débris, might interfere with the reasonable 50 expectations of such landing operations. And in like manner the use of water ballast containers from the ship by the crew on board, would be equally subject to uncertainties, so that the use of sponges lowered-away 55 in cages offers the opportunity of absorbing and retaining water through a multitude of natural valves, with the capillary action in the sponge, so that it affords a guarantee of the absorption of about twenty times the weight of the material carried by the ship 60 for this purpose. The quick absorption by sponges or like material may at times entail the "priming" of the sponges in order that their absorption of water is more rapid and complete, but in any event the formation of 65 the sponges affords the opportunity of the

quick increase of weight content, and, on the other hand, provides for a quick expulsion of a substantial amount of the weight, as indicated in Fig. IX, and thereafter by drawing the sponge cage adjacent the crew's quarters 70 on the ship it is a simple matter to provide for the complete expulsion of the water and the dry storage of the sponges to minimize weight, with the added advantage that in case of emergency for the extreme lightening 75 of ship ballast even the weight of sponges or other material of similar physical characteristics may be jettisoned. While a sock might in some cases be used in place of the sponge-anchor, that is a container such as a 80 canvas bag, collapsible and easily stored on board ship, or other form of anchor having the qualifications essential for the purposes herein described,—any such means would require a valve to assure the inlet and exit of 85 water. Therefore the use of sponges with the innumerable inlets for water, it will be noted is under certain circumstances to be preferred instead of any anchor ballast space dependent upon the functioning of valves. 90

It will thus be seen that in the practice of this invention the present day requirements for airship landing, namely a large ground crew and haul-down ropes, are unnecessary, and in place thereof it brings a fixed part of 95 the ship's hull at its lowest portion, into cushioning contact with the surface of the water, thereby relieving weight, but simultaneously it permits the taking on of ballast under absolute control, namely, by the opening of valves to the desired degree. Then should the wind or the buoyancy conditions of the ship tend to cause it to ascend, a slight 100 rise of the ship immediately brings into effect the counter-weight of the water ballast that has been allowed to enter the ballast hull at the bottom. Tons of water in this way, or only pounds of water, may be added to the ship's ballast for stable flotation and may be definitely regulated, and in particular the 105 weight of ballast in that way acquired may be quickly discharged in part or whole,—all under the control of the crew on board. The sponge-anchors or their equivalent, may be used to bring the ship down for water landing when it has no headway, and a suitable 110 number and arrangement of such "anchors" may alone serve to maintain the ship in stable flotation on the surface in conjunction with the nacelle keel, without admitting water-ballast to the keel. But it is preferable to use anchors for lowering the ship and then regulate the flotation by some water-ballast, so that the "anchors" may be cleared and the 115 expulsion of the water-ballast used for getting under way, under entire and quick control of the crew. 120

The under-water lines of the nacelle keel may be constructed in various ways to break contact from the water surface at the speed of 130

takeoff; while also supplementary propellers, or a propeller operated through gear from the ship may be used for the minor maneuvers of the ship when moored on the water.

5 In Figs. VI, VII, VIII and IX the airship 1^a has the nacelle 24 which may be arranged and equipped like the nacelle shown in the previous figures, or may be only for flotation purposes to counteract the weight provided by the hold-down-anchors. It may also have one or more break-water keels 25 to cushion the landing of the ship on the water by providing a gradual emersion of the nacelle. In compartments 26—26, located fore-and-aft where they will preferably be above any emersion, suitable gear, such as the reel 27, provides for manipulating anchor-cables 28 passing out of the hull on either side over suitable sheaves and guides at 29—29. These lines 28 are each attached to an anchor 30. In the form shown the anchor is a cage containing sponges, and another line 31 from each cage leads to compartment 26, thus providing means for pulling the anchor 30 inboard within the grasp of the crew, in order to fully expel the water from the sponges and stow away that landing gear when in flight. In the form shown in Fig. IX a second line 32 runs to the ship passing through the guide 33 and secured at 34 to a plurality of radiating lines 35, which in turn are secured to joints 36 in the hinged connections of the bottom of the cages 37. In this form provision is made for the sponges 35 to be spread out when absorbing water and functioning in a weight capacity, and when it is desired to lighten the ballast preliminary to weighing anchor, the line 32 is first hauled in and through the connections with the lower members of the cage or basket, it compresses the mass of sponges, expelling the water and thereby lightening the weight of the anchors until they can be hauled close to the ship and inboard by lines 31 to complete the drying of the sponges.

As shown in Fig. VI the anchors 30 are emersed with the ship's keel above the surface of the water, in the operation of lowering the ship for a water landing. In Fig. VII an end view shows the ship's nacelle 24 emersed in the water with the anchors also emersed, thus providing central flotation and lateral control, the balance of which may be regulated by the crew, and during the mooring the anchor lines as well as the nacelle ballast, if water has been admitted, will be constantly under the control of the crew for trimming of ship to meet the aero-static conditions, and also to vary the flotation with any variation of load by taking on or discharging cargo, supplies or personnel.

It will thus be seen that by my invention an airship may be made stable for flight with a keel that can be a complementary part, or an integral part of the lower keel structure

of an airship, and the moment water landing is desired, the manipulating of the permanent equipment of the ship provides for grasping a sufficient ballast or load weight, controlled entirely by the ship's crew, in order that the ship be brought down to the surface, and then held down to the surface of the water in stable flotation. With this condition, the ship's crew alone is in a position to release part or all of the ballast, synchronized with all other operations of getting the ship underway.

While the use of a specially arranged islet with a mooring tower or mast has certain advantages, the invention is of particular importance for mooring to watercraft, by lying in their lee, or mooring to a shore tower with a constant prevailing off-shore wind, or under suitable conditions mooring on the surface of the water without depending upon any floating or stationary mooring mast or like device.

Various additional advantages will be realized from the practice of my invention, and many variations in the construction, beyond the particular forms herein specifically shown and described, may be made without departing from my invention.

What I claim and desire to secure by Letters Patent is:

1. An airship having self-contained means for adding temporarily to its load a controlled amount of water, said means including a submersible anchor controlled by a cable from the ship to a water surface, and means integrally incorporated in the lower portion of the ship for buoyancy on a water surface, and having controlled means for the admission and expulsion of water-ballast.

2. A rigid airship having integrally embodied with its structure a hull a substantial length of the lowest portion of the ship adapted to ride on a water surface, means incorporated therewith for admitting water-ballast and expelling water-ballast, and one or more water-anchors adapted to be lowered and retracted from the ship to take an increased water load for lowering said ship to the surface for the engagement of the integral structure of the ship's bottom and the emersion thereof in the water, whereby the ship may be brought to a water surface and moored thereon in stable flotation by means entirely controlled by the ship's crew.

3. A rigid airship having one or more pairs of sea-anchors embodying means for acquiring and retaining an added water load, means on the ship for lowering and hoisting said sea-anchors, one of each of said pair of sea-anchors being on opposite sides of the keel of the ship, whereby lateral trim and rolling of the ship may be controlled by the crew.

4. A rigid airship having self-contained means for lowering and raising a dependent

cage or the like containing sponges, or material of similar physical characteristics.

5. A rigid airship having a watertight keel for part of its length extending below the

5 main hull for a minor part of the length of the ship and having its sides converging to a narrow kelson and having an airtight roof and means on board ship above the airtight roof adapted to control the admission of air 10 into said keel, and one or more valves permitting ingress and exit of water from the bottom of the keel, said means of control therefor closely assembled in an operating compartment of the ship.

15 6. In an airship, a rigid hull structure with a rigid longitudinal girder extending along the bottom of the main hull, a water chamber structure supported below a minor part of said main hull structure and having 20 stream lined sides extending from the skin of the main hull with sides sharply converging to a narrow kelson, water-ballast inlets at the lowest part of said water-ballast hull, and controlling means therefor actuated 25 from a part of the main hull.

7. In an airship self-contained means operable by the ship's crew to add water load from an underlying body of water, means associated therewith to draw the ship to the 30 surface of the water, and means for floating contact of the keel of the ship on the water surface and for controlling excess water-ballast in the keel.

8. A rigid airship having self-contained 35 means operable by its crew to add a remote water-weight from a water-body below the ship, means on the ship for drawing the ship to the below lying water surface, and means for resisting the submersion of the ship be-

40 yond the keel, whereby the airship may be drawn to the water surface and maintained in stable flotation under the control of its own crew.

9. A method of mooring airships consisting of lowering away from the ship means 45 acquiring added dead weight from an underlying body of water, drawing the ship down by the resistance of such excess temporary weight without unnecessary reduction 50 in buoyancy of the ship's flotation gas, bringing the ship to a semi-emersion of a keel section, thereupon manipulating water-ballast in the keel in conjunction with the super-water-load means, and maintaining thereby 55 stable flotation on the water surface.

10. The method as set forth in claim 9, having as an additional operation the mooring of the ship by-the-bow to a strain-resisting 60 object, and adjusting the trim in respect of the bow strains, keel flotation and temporary excess loads into stable flotation against rise and fall and rolling.

11. A rigid airship having self-contained 65 means for lowering and raising a dependent

cage or the like containing sponges, means embodied in said cage and remote control on the ship for evacuating the water from said sponges.

12. A rigid airship having self-contained 70 means for manipulating a dependent cage or the like adapted to absorb a water load, and means on the ship for controlling the absorption or evacuation of said water load in the dependent cage.

13. A rigid airship having self-contained 75 means for raising or lowering a cage or the like equipped for absorption of water by capillary action, and remote control on said ship for evacuating the water.

14. An airship having self-contained 80 means for controlling a remote water load dependent from the ship, said water load comprising sponges or the like, and having means for squeezing or otherwise evacuating 85 the water from said sponges under control from the ship.

15. A rigid airship having one or more dependent cages for sponges, means on the ship for lowering or raising each cage, and means 90 on the ship for reducing the water content in said sponges.

16. A method of mooring airships consisting of lowering from the ship means for capillary or like absorption of water underlying the ship, drawing the ship down by the deadweight due to the absorbed water in said means, bringing the ship to contact with the water surface, and thereupon maintaining stable flotation on the water surface by the 95 control of waterweight.

In testimony whereof, I have signed my name to this application, this 13th day of January, 1930.
